UNITED STATES PATENT OFFICE.

CHARLES LOUIS HANSEN, OF RACINE, WISCONSIN, ASSIGNOR TO GOLD MEDAL CAMP FURNITURE MANUFACTURING CO., OF RACINE, WISCONSIN, A CORPORATION OF WISCONSIN.

FOLDING COT.

1,115,813.

Specification of Letters Patent.

Patented Nov. 3, 1914.

Application filed November 21, 1910. Serial No. 593,328.

To all whom it may concern:

Be it known that I, CHARLES LOUIS HANSEN, a citizen of the United States, residing at Racine, in the county of Racine and State 5 of Wisconsin, have invented certain new and useful Improvements in Folding Cots, of which the following is a specification, reference being had to the accompanying drawing, forming a part thereof.

10 This invention relates more particularly to folding cots having metal frames, and its main object is to produce a comparatively light and at the same time rigid or stable and durable frame for such cots which can 15 be easily and quickly folded into small compass or set up for use, and when spread and adjusted for use will be firm and stable and will not accidentally collapse.

It consists in the construction, arrangement and combination of parts as herein-after particularly described and pointed out in the claims.

20 In the accompanying drawing like characters designate the same parts in the several 25 figures.

Figure 1 is a plan view showing a cot embodying the invention spread or set up ready for use; Fig. 2 is an end elevation of the same on an enlarged scale, certain parts 30 being broken away and shown in section; Fig. 3 is a side elevation showing the frame of the cot as partially folded; Fig. 4 is a side elevation showing the frame completely folded; Fig. 5 is a greatly enlarged cross 35 section on the line 5-5, Fig. 4; Fig. 6 is an enlarged detail view of a portion of one of the side rails and one of the end legs with the brace for holding the leg in operative position, looking in the direction of the arrow 6, Fig. 2; Fig. 7 is an inside or top view of the joint between one of the middle legs and the adjoining sections of a side rail, showing the parts unfolded and in position 40 for use; Fig. 8 is a vertical section on the line 8-8, Fig. 7; Fig. 9 is a view similar to Fig. 7 showing the parts folded; Fig. 10 is an enlarged detail view showing an end of one of the side rails in side elevation with one of the angle-form cross pieces or spreaders engaged therewith in cross section on the line 10-10, Fig. 2; Fig. 11 is an elevation similar to Fig. 2, showing a pair of legs folded; and Fig. 12 is a cross section on the line 12-12, Fig. 11.

The folding cot frame comprises two side

rails, each composed of two sections *a*, three pairs of legs *b* and *c*, and two detachable cross or end pieces or spreaders *d*.

The main members of the frame are constructed of comparatively light sheet metal 60 of angle-form in cross section, preferably with a wide flange *x* on one side and a narrow flange *y* on the other side of an intervening web *z*, as shown in Figs. 6, 7, 8, 9 and 10, for the purpose not only of securing 65 the desired strength and rigidity with as little weight as possible, but also of facilitating the folding of the frame into small compass. Some or all of the members may however, be made with but one flange, the 70 narrow flange being omitted.

The sections *a* of the side rails are pivotally connected adjacent to their inner ends by rivets *e* with the cross arms of T-fittings *f*, placed on the inner or upper side of the 75 wide flanges *x* of said section, with reinforcing plates *g* on the outer or under side of said flanges, as shown in Figs. 7, 8 and 9, so that when the frame is unfolded and the sections *a* are brought into line with each 80 other, their inner ends will abut, as shown in Fig. 7, and tend, as in rule joints, to hold them in alinement. The middle legs *b* and *c* are riveted or rigidly fastened at their upper ends to the middle members or stems of the 85 plates or fittings *f* at right angles to the cross pieces or members thereof as shown in Figs. 7, 8 and 9. The upper ends of the end legs *b* and *c* are pivoted by rivets *h* to the inner or upper sides of the wide flanges *x* 90 of the side rails *a*, adjacent to their outer ends, so that they can be folded inwardly as indicated by dotted lines in Fig. 6, parallel with the side rails into the channel or space between the wide flanges on the outer 95 sides thereof when they are brought together, as shown in Fig. 5, and can be turned outwardly in setting up the cot into positions perpendicular to or a little beyond a perpendicular to the side rails, as shown by 100 full lines in Fig. 6. Each of the end legs is connected with the outer end of the adjacent side rail by a brace *i* which is pivoted at one end to the leg and connected at the other end with the side rail by a link *j*, 105 which when the leg is unfolded, lies parallel with the side rail, bearing along its upper edge against the inner side of said rail and extending at its free end beyond its pivot connection with the brace *i* to a point 110.

2
approximately flush with the end of said rail, as shown by full lines in Fig. 6.

To lock and hold the side rails spread apart and the duck or canvas top or cover *k* which connects them, stretched taut, and to prevent the cot when set up from accidentally closing, the cross pieces or spreaders *d* are provided. These cross pieces like the other main members of the frame, are made of sheet metal in angle-form, preferably with flanges of the same width on both sides. The flange on one side of each cross piece is formed adjacent to its ends with transverse notches fitted to engage and interlock with corresponding longitudinal notches *l* in the ends of the side rails *a*, as shown in Figs. 2, 6 and 10, the wide flanges of the side rails being cut away as shown in Fig. 10, to permit the ends of the rails to enter the channel of the cross piece without necessarily increasing the width of the latter. The flange on the opposite side of each cross piece *d* is formed or provided with inwardly projecting lugs *m*, which are arranged to engage with the links *j* at one end of the cot and to lock and hold them in place with the associated braces *i* and legs *b* and *c* connected therewith, in operative position, as shown in Figs. 1, 2 and 6. These detachable cross pieces or spreaders *d* are made of such width that they will readily fit over the middle legs *b* and *c*, as shown in Figs. 3, 4 and 5, when the cot is folded. One leg *b* of each pair has the web, narrow flange and channel or a flange formed on one side thereof at one end and on the opposite side thereof at the other end, or on opposite sides of its pivot connection with the other leg *c*, as shown in Figs. 2 and 11, the two legs of each pair being pivotally connected at or adjacent to the center thereof by a rivet or pin *n*.

A plate *o* is folded over and riveted to the webs or flanges on opposite sides of each leg *b*, as shown in Figs. 2, 11 and 12, and forms a bearing for the head of the rivet *n* which is shouldered where it passes through the wide flanges of each pair of legs as shown in Fig. 12, so as to hold them close together.

Each leg *c* has the narrow flange, web and channel or a flange formed on one side thereof only, and being pivoted on the rivet *n* between the wide flange of the leg *b* and the plate *o*, is thus adapted to fold into the channels or recesses on the opposite sides and at the opposite ends of the leg *b*, as shown in Fig. 11. The webs or flanges of each leg *b* and the overlying folds of the plate *o* are cut away so as to engage with opposite sides or edges of the associated leg *c* and form stops, as shown in Fig. 2, for limiting the spread or opening of the legs and preventing collapse of the cot independently of the top or cover *k*. The plate *o* serves also as a reinforcement for each pair

of legs adjacent to their pivot connection with each other, as well as forming a bearing for the pivot rivet *n* and stops for limiting the spread of the legs.

The top or cover *k* of the cot, which may be made of duck, canvas, or other suitable fabric, may be fastened to or held in place on the frame in any suitable manner, as by wide hems along the sides through which the side rails *a* are inserted, and corresponding hems at the ends through which the removable cross pieces or spreaders *d* are inserted when the cot is set up. The top or cover is cut away, as shown in Fig. 1, adjacent to the corners and to the middle joints, so as not to interfere with the folding and unfolding of the frame and to prevent injury to the fabric.

In folding the cot, it is preferably inverted as shown by Fig. 3, and, the cross pieces or spreaders *d* being detached and removed, the several pairs of legs *b* and *c* are folded as shown by Fig. 11, thus bringing the rail sections *a* together, the cloth top or cover *k* folding longitudinally and hanging loosely below them. The end legs are then folded inwardly on their pivots *h* into the channel or space between the wide or outer flanges of the side rail sections *a*, as shown by Figs. 3, 5 and 6; the cross pieces or spreaders *d* are placed over the middle legs as shown by Figs. 3 and 5, and the sections *a* of the side rails with the end legs are folded on the pivots *e* into place on opposite sides of and parallel with the middle legs, as shown by Figs. 4, 5 and 9. The top or cover *k* is finally wrapped around the folded frame and preferably secured in place thereon by straps or other fastenings (not shown).

By the construction of the main members of the frame of sheet metal in angle-form, and their arrangement as herein shown and described, a strong, rigid and at the same time comparatively light metallic frame is produced, which can be easily and quickly folded into compact and convenient form for transportation or storage.

I claim:

1. In a folding cot, a metal frame comprising angle-form side rails and angle-form legs pivotally connected with one another in pairs to fold crosswise of the side rails and pivotally connected at their upper ends with the side rails to fold lengthwise thereof, one leg of each pair being adapted to fold into and parallel with the other and the folded end legs being adapted to fold between into and parallel with the side rails.

2. In a folding cot the combination of side rails, legs pivotally connected with one another in pairs to fold crosswise of the side rails one into and parallel with the other and pivotally connected with the side rails adjacent to their ends to fold lengthwise thereof

into, between and parallel with the same, and folding braces pivoted at one end to the legs and connected at the other end with said rails between the outer ends thereof and the 5 upper ends of the legs by links, which when the legs and braces are unfolded bear lengthwise against the under side of said rails.

3. In a folding cot the combination of angle-form side rails, angle-form legs pivotally connected in pairs and at one end with 10 said rails, braces pivoted at one end to said legs and connected at the other end with said rails by links, and notched angle-form cross bars fitted to engage with the ends of said 15 rails for holding them apart and provided with lugs adapted by engagement with said links to hold the legs in operative position.

4. In a folding cot the combination of side rails composed of sections, end and middle 20 legs pivotally connected in pairs and at one end with the side rails and adapted to fold together parallel with the rail sections, and angle-form cross pieces removably fitted to the ends of said rails for holding them apart 25 when the cot is spread and adapted to fit over and inclose the folded middle legs when the cot is folded.

5. In a folding cot, a metallic frame comprising legs of angle-form pivoted together

in pairs between their ends, one leg being 30 formed on opposite sides thereof with flanges, one on each side of its pivot connection with the other leg, the latter leg being fitted to fold lengthwise into and parallel with the former leg, and a plate folded over 35 and fastened to the inner ends of said flanges and forming stops for limiting the spread of the legs and a bearing for the pivot pin.

6. In a folding cot, a metallic frame comprising legs of angle-form pivoted together in pairs between their ends by a shouldered rivet, one leg being formed on opposite sides thereof with flanges, one on each side of its pivot connection with the other leg, the latter leg being fitted to fold inside of the former leg, and a plate folded over and fastened to the inner ends of said flanges and forming a bearing for the rivet and a reinforcement of the legs adjacent to said pivot 45 connection.

In witness whereof I hereto affix my signature in presence of two witnesses.

CHAS. LOUIS HANSEN.
